DRAINAGE MEANS FOR TANK ROOFS

John H. Wiggins, Chicago, Ill.

Application, March 11, 1940, Serial No. 323,297

1 Claim. (Cl. 220—35)

This invention relates to large metal tanks of the kind that are used in oil fields to store petroleum products.

The object of my invention is to provide an oil storage tank whose component parts are combined in a novel manner that simplifies and reduces the cost of the supporting structure for the roof of the tank, and also provides a reliable drainage means for the tank roof that is not affected by freezing weather.

Briefly described, my improved tank is composed of a vertical side wall, any suitable type or kind of roof attached to said side wall, such, for example, as a breather roof or balloon roof, a drain water collection chamber or receiving chamber arranged so as to receive drain water from the roof, and made of a diameter great enough to practically eliminate the possibility of water freezing in said chamber and bursting the same, and an eductor leading from said collection chamber and designed, constructed or arranged so that if, for any reason, the escape of water from said eductor is cut off or prevented, water will not freeze in said eductor and burst or disrupt same. The collection chamber or receiving chamber is arranged inside of the tank and attached to or combined with the tank in such a manner that the drain water in said chamber cannot come in contact with or contaminate the material or substance confined in the tank. Any suitable means may be used to cause water that falls onto the tank roof to be discharged into or conducted to said collection chamber. The eductor, which is arranged inside of the tank, adjacent the bottom of same conducts drain water from the collection chamber to a sewer or to a point outside of the tank, and said eductor is of such construction and arrangement that there will always be an air space in said eductor, above the level of the water therein, irrespective of whether said eductor is functioning properly, or is in an inoperative condition. Said air space effectively prevents the eductor from filling with water to such an extent or degree as to cause the eductor to burst, in the event the water therein freezes solid.

Figure 1 of the drawing is a transverse vertical sectional view of a liquid storage tank equipped with a roof drain constructed in accordance with my invention.

Figure 2 is a fragmentary sectional view, illustrating how said drain acts, in the event the outlet of the eductor becomes clogged, or in the event the rate of discharge of water from the eductor becomes materially less than the rate at

which drain water enters the eductor from the collection chamber.

Figure 3 is a sectional view, taken on the line 3—3 of Figure 1.

Figure 4 is a fragmentary transverse vertical sectional view, illustrating another kind of eductor that may be used.

Figure 5 is a sectional view, taken on the line 5—5 of Figure 4; and

Figure 6 is a perspective view of one of the partition plates used in the eductor shown in Figure 4.

In the drawing A designates a large metal tank that is adapted to be used for storing liquid 15 x, and B designates the top or roof of said tank. I have herein illustrated my invention in connection with a metal tank roof of the type or kind that is adapted to flex upwardly and downwardly so as to vary the volume of the vapor space of 20 the tank, but I wish it to be understood that my invention is applicable to rigid tank roofs, and in fact, to any type or kind of tank roof that employs a drain or drainage means, and which is used in a locality where freezing water is a 25 problem that has to be reckoned with, in order to insure proper functioning and safe operation of the tank. The tank roof B herein shown is so shaped or formed that when it is in its normal downwardly flexed condition, water that falls onto the top side of said roof will flow or drain to a discharge device or drain opening at the center of the roof, and when it is in its upwardly flexed condition, as shown in Figure 1, water that falls onto the top side of the roof will flow or 30 drain outwardly towards the peripheral edge of the roof and escape from same. When the roof is in its normal downwardly deflected condition, it is substantially dish-shaped, and at such times the roof is supported by a supporting structure, usually formed from roof beams 1 that extend radially from the center of the tank to the upper edge portion of the side wall of the tank.

My improved drain or drainage means comprises a receiving chamber or collection chamber C arranged inside of the tank and formed preferably by a vertically-disposed, tubular member 2 that extends upwardly from the center of the bottom 3 of the tank to a point above the level of the liquid in the tank, and an eductor D for conveying water out of said collection chamber, and discharging said water into a sewer F, or onto the ground at a point outside of the tank, said collection chamber and eductor being so constructed and combined with the tank that the water in said chamber and eductor cannot con-

taminate or mix with the liquid x confined in the tank.

While my broad idea contemplates the use simply of a drain hole in the tank roof, arranged so as to discharge drain water into the collection chamber C, I prefer to equip the roof with a burst-proof drain water discharge device of the liquid sealed type, such, for example, as a conventional inverted siphon drain, composed of a short, vertically-disposed pipe 4 that leads downwardly from a sump 5 at the center of the roof, and a relatively shallow cup or receptacle 6 attached to the lower end of said drain pipe 4 in such a way that the water in said cup will seal the pipe 4, and the water that enters the receptacle 6 from the pipe 4 will overflow the edge of said receptacle and drop downwardly into the collection chamber C. Owing to the fact that the cup or receptacle 6 is relatively shallow, there is no danger of said receptacle being broken or injured by water that freezes solid in said receptacle. The collection chamber C is of relatively great diameter, so as to tend to reduce the possibility of water freezing in said chamber and bursting the same, and in the form of my invention herein shown the chamber C is formed from a vertically-disposed metal cylinder 2, having its lower end connected by a welded joint 7 to the bottom 3 of the tank, and made of such height that it will serve as a supporting means for the roof beams 1, whose outer ends are attached to the side wall of the tank. In order that my improved drainage means will not cut down the storage capacity of the tank, I prefer to make the tubular member or cylinder 2 of the same height as the depth of the side wall proper of the tank, and attach an extension or collar 8 to the top edge of the tank side wall, so as to provide for the downward flexing of the roof and maintain the roof supporting beams 1 in an inclined position, sloping upwardly from the center of the tank.

The eductor D may consist of any suitable kind of conduit at the bottom of the tank that is either combined with the collection chamber C in such a manner, or which is of such construction, that it is impossible for said eductor to become completely filled with water, even though the escape or discharge of water from said eductor is cut off. In the form of my invention shown in Figures 1 and 2 this result is attained by providing the eductor D with an inlet opening and a discharge opening located at a point far enough below the top of the eductor, that if the escape or discharge of water from the eductor is interrupted, as for instance, due to the clogging of the outlet of the eductor, air will collect in the upper portion of the eductor, and thus prevent the eductor from becoming completely filled with water entering same from the collection chamber. Inasmuch as the eductor can never become completely filled with water, it is impossible for said eductor to burst or to be disrupted, due to water in same freezing solid. The eductor D shown in Figures 1 and 2, is formed from a metal plate bent into substantially inverted channel shape and connected by welded joints 9 to the bottom of the tank, thereby producing a rectangular-shaped conduit on the bottom of the tank, whose inner end is attached by a welded 65 or other water-tight joint 10 to the tubular member 2, which constitutes the collection chamber C, and whose outer end is attached by a welded or other water-tight joint 11 to the side wall 70 of the tank. Said eductor D is provided with an 75

inlet 12 through which water is admitted to the eductor from the collection chamber C, and it is also provided with an outlet or discharge opening 13 through which water escapes from the eductor. As shown in the drawing, said inlet 12 and outlet 13 are located considerably below the top or upper side of the eductor D. Usually, the outlet or discharge of the eductor D will comprise a trap or inverted siphon 14 which co-acts with the inverted siphon device on the roof of the tank to make the tank gas-tight, and if desired, a control valve 15 covered with insulation 15a can be arranged between the trap 14 and the outlet 13 through which the drain water escapes from the eductor D.

Under normal conditions, when the roof occupies such a position that water which falls onto the roof will find its way to the discharge device formed by the elements 5 and 6, the drain water will escape from said discharge device into the collection chamber C, then through the opening 12 at the lower end of said chamber into the eductor D, and thence from the eductor into the sewer E or other point of discharge, through the discharge opening 13 of the eductor and the trap 14 that leads from said discharge opening. If the outlet of the eductor becomes clogged, water will continue to flow from the collection chamber into the eductor until the water in the eductor rises high enough to submerge the openings 12 and 13 and trap air in the upper portion of the eductor that is used to create a force or pressure which effectively resists the escape of water from the collection chamber C into the eductor, and which eliminates the possibility of the eductor D becoming completely filled with water. If, for any reason, water cannot get out of the eductor, then the highest possible level that water can rise in the eductor at atmospheric pressure, is the top of the inlet and discharge openings 12 and 13, the water in the collection chamber C continuing to rise. Under these conditions a pressure equal to a column of water the height of the tubular member 2 will be set up in the eductor D. The normal height of conventional oil storage tanks is about 40 ft., and consequently, a little over one atmospheric pressure will be set up in the eductor, and the air in the air space in the upper portion of the eductor, above the level of the water in the eductor, will be compressed accordingly, but there will still be ample space left so that in the event the water in the eductor freezes solid, the ice can expand into the air space in the upper portion of the eductor. The drain discharge device on the roof of the tank can freeze solid, without liability of breaking, on account of the fact that the receptacle 6 of said device is made relatively shallow. When the apparatus is equipped with a trap or siphon 14 that forms part of the outlet from the eductor and which is usually buried in the ground, there is little liability of water freezing solid in the siphon 14, and causing it to burst. Consequently, my improved drainage means conducts drain water from the roof into a sewer, or to a point on the exterior of the tank, without danger of contaminating the liquid confined in the tank, and with little liability of the co-acting parts of the drainage means freezing solid and bursting in cold weather. In addition to having the desirable characteristics above mentioned, my improved tank roof drainage means is inexpensive to construct, as it is composed of a relatively few parts of simple design and rugged construction that can easily be

combined with the tank. Inasmuch as the vertically-disposed, tubular member 2 that constitutes the collection chamber C is arranged at the center of the tank, it can be used as a center support for the roof beams 1, thereby reducing the cost and simplifying the construction of the supporting means for the tank roof.

In Figures 4 and 5 of the drawing I have illustrated another form of eductor that may be used. Said eductor consists of a pipe or conduit B', of circular shape in cross section, mounted on the bottom of the tank between the tank side wall and the vertically-disposed, tubular member 2, and attached by welded joints or other suitable water-tight connections to said member and side wall, and provided intermediate its ends with a plurality of transversely-disposed partition plates 16 arranged in the upper portion of the eductor B'. The partition plates 16 can be easily installed in or combined with the pipe that constitutes the eductor D' by sawing slots in the top side of said pipe, arranging partition plates 16 in said slots, and then securing said partition plates to the pipe by welded joints 17, as shown in Figure 4. Such an eductor can never be filled with drain water to such an extent that the eductor will burst when the water in same freezes solid, due of course, to the fact that when the water in the eductor rises above the bottom edges

of the partition plates 16, a plurality of pockets or cushions of air become trapped in the upper portion of the eductor D'. Said eductor can be sloped any reasonable amount, the degree of sloping of said eductor being determined by the spacing of the partition plates or separators 16.

Having thus described my invention, what I claim as new and desire to secure by Letters Patent is:

- 10 An oil storage tank provided at its center with a water collection chamber formed by a vertically-disposed, tubular member of relatively great diameter, attached at its lower end to the bottom of the tank and having its upper end open and terminating inside of the tank above the level of the oil in the tank, a roof, a supporting structure for said roof, attached to said centrally-disposed, tubular member and projecting upwardly and radially from the upper end of said member, said roof having a drain opening through which drain water is discharged from the roof into said collection chamber under certain conditions, and an eductor on the bottom of the tank, projecting radially from said center tubular member and provided with inlet and discharge openings located below the horizontal center of said eductor.
